US00D862183S

(12) **United States Design Patent** (10) **Patent No.:** **US D862,183 S**
(45) **Date of Patent:** **** Oct. 8, 2019**

(54) **REACHING TOOL**

(71) Applicant: **Otis Elevator Company**, Farmington, CT (US)

(72) Inventors: **Benjamin Alan Browne**, Stuart, FL (US); **Robert Rodriguez**, Phoenix, AZ (US); **Paul Hegele**, Grand Rapids, MI (US)

(73) Assignee: **OTIS ELEVATOR COMPANY**, Farmington, CT (US)

(**) Term: **15 Years**

(21) Appl. No.: **29/622,915**

(22) Filed: **Oct. 20, 2017**

(51) LOC (12) Cl. **08-05**

(52) U.S. Cl.

USPC **D8/14**

(58) **Field of Classification Search**

USPC D8/14, 51, 367, 394
CPC ... A47G 33/10; B25G 1/04; F21S 4/10; F21V 19/04; F21V 21/08

(57) **CLAIM**

We claim, the ornamental design for a reaching tool, as shown and described.

DESCRIPTION

FIG. 1 is a perspective view of reaching tool, showing our new design in a first embodiment;

FIG. 2 is another perspective view thereof;

FIG. 3 is a side elevation view thereof;

FIG. 4 is another side elevation view thereof;

FIG. 5 is a top plan view thereof;

FIG. 6 is a bottom plan view thereof;

FIG. 7 is a front elevation view thereof;

FIG. 8 is a rear elevation view thereof;

FIG. 9 is a perspective view of reaching tool, showing our new design in a second embodiment;

FIG. 10 is another perspective view thereof;

FIG. 11 is a side elevation view thereof;

FIG. 12 is another side elevation view thereof;

FIG. 13 is a top plan view thereof;

FIG. 14 is a bottom plan view thereof;

FIG. 15 is a front elevation view thereof; and,

FIG. 16 is a rear elevation view thereof.

The broken lines depict portions of the reaching tool in which the design is embodied that are not considered part of the claimed design.

1 Claim, 10 Drawing Sheets
